RAILWAY TRAFFIC CONTROLLING SYSTEM

Winthrop K. Howe, Rochester, N. Y., assignor to
General Railway Signal Company, Rochester,
N. Y.

Application December 19, 1931, Serial No. 582,108

9 Claims. (Cl. 246—3)

This invention relates to traffic controlling systems for railroads, and more particularly pertains to the remote control of power operated track switches.

5 The present invention contemplates a control system for power operated track switches in which the operation of a track switch is prevented from being initiated during the occupied condition of an associated detector track section; and 10 also in which an operation of the track switch already initiated is caused to be completed upon the entrance of a train into the associated detector track section, which is generally more desirable in such cases, than causing a switch to be 15 stopped in mid stroke.

Various other features, advantages and characteristic functions of the present invention will be in part pointed out, and in part obvious from the accompanying drawing, as the description 20 progresses.

In describing the invention in detail, reference will be made to the accompanying drawing which illustrates in a simplified and diagrammatic manner the circuits and parts of a switch machine 25 control system embodying the present invention.

With reference to the accompanying drawing, a railroad track switch TS is indicated as being operated by a switch machine SM of any suitable type, such for example, as disclosed in my 30 Patent No. 1,466,903, dated September 4, 1923. This switch machine has associated therewith a control relay CR together with normal and reverse contactors N and R for governing the normal and reverse operating circuits of the usual armature A and field winding F. These relays may be located within the switch machine structure or 35 may be suitably provided with a separate housing, as desired. Also, inasmuch as these relays open and close the operating circuits of the switch machine motor, the usual pole changer contacts and pole changer coils are omitted. The switch machine SM is provided, however, with suitable point detector contacts and associated mechanism, as shown for example in the patent to C. S.

40 Bushnell Patent No. 1,517,236, dated November 25, 1924, which mechanism includes two pair of fixed contacts 2 and 3 together with movable contacts 4 and 5. The movable contacts 4 and 5 are jointly operated by the track switch TS and 45 the switch machine SM so as to assume normal or reverse positions when the track switch TS is in normal or reverse extreme locked positions respectively, and so as to assume intermediate mid stroke positions whenever the track switch 50 TS is being operated by the switch machine SM or whenever the track switch TS is unlocked.

The control relay CR is preferably of the polarized type having its contact 6 operated to opposite extreme positions upon the application of potential of opposite polarities to its windings. How-

ever, the contact 6 is preferably held, irrespective of continual energization of the relay, in its last operated position by either a magnetic stick structure or a suitable mechanical toggle arrangement.

65 The normal and reverse contactors N and R are of the neutral marginal type, that is, when their operating windings 7 and 8 respectively are energized at the same time that their holding windings 9 and 10 respectively are energized, their contacts will be picked up, but if only the holding windings are energized their contacts will not pick up. Also, if the contacts of these contactors are once picked up and only the holding windings are energized, then the contacts will remain in 75 picked up positions.

Associated with the track switch TS is the usual detector track section having a track battery and the usual track relay T. It is also to be understood, that there are suitable signals (not 80 shown) associated with the track switch TS for governing traffic thereover in accordance with standard practice.

The control relay CR is operated in accordance with the manual actuation of a switch machine 85 control lever SML, located in the tower, over a suitable polarized line circuit. The switch machine lever SML may be of any suitable type, that is, it may be a free lever as illustrated with suitable electric interlocking associating it with the 90 remainder of the system, or it may be the usual mechanically interlocked lever having associated therewith suitable detector locking and the like, as disclosed for example in my Patent No. 1,550,611, dated August 18, 1925. Suitable approach locking means may also be incorporated 95 when desired.

A battery BT has been illustrated as supplying the power for the control and operating circuits over bus wires 12 and 14, it being understood of course that any other suitable source may be employed. The bus wires 12 and 14 are considered as extending from the tower or power house to all of the outlying switch machines.

105 It is believed that the nature of the invention, its advantages and characteristic features can be best understood with further description being set forth from the standpoint of operation.

Operation

110 With the control lever SML in its present normal position, the control relay CR is energized by a circuit from the positive bus 12, through wires 20 and 21, contact 22 of lever SML in a normal position, wire 23, windings of relay CR, wire 115 24, contact 25 of lever SML in a normal position, wire 26, to the negative bus 14.

Assuming traffic conditions are such as to properly condition the associated interlocking means (not shown)—either electric or mechani- 120

cal) and that the detector track section associated with the track switch TS is unoccupied, track relay T is therefore energized. Under these conditions, if the operator moves the switch machine lever SML to the opposite position, the polarity is reversed on the control relay CR thereby actuating polar contact 6 to its opposite position. For example, the movement of contacts 22 and 25 to reverse positions causes a reversal of 10 current by completing a circuit from the positive bus 12, through wires 20 and 27, contact 25 of lever SML in a reverse position, wire 24, windings of relay CR, wire 23, contact 22 of lever SML in a reverse position, wire 26, to the negative bus 14.

15 The contact 6 of relay CR in a right hand position completes a pick-up circuit for the reverse contactor R from the positive bus 12, through wires 28 and 29, contact 6 of relay CR in a right hand position, wire 30, point detector contacts 2-4, wire 31, pick-up winding 8 of reverse contactor R, wires 32 and 33, front contact 34 of track relay T, wire 35, to the negative bus 14. At the same time that the pick-up winding 8 is energized, the holding winding 10 is energized through a circuit from the positive bus 12, through wires 28 and 29, polar contact 6 of relay CR in a right hand position, wire 30, point detector contacts 2-4, wire 31, holding winding 10 of reverse contactor R, wire 36, to the negative bus 14.

20 With both the pick-up and holding windings energized, the degree of energization of the reverse contactor R is sufficient to cause the contact 37 to be actuated to a picked up position, in which position it closes the reverse operating circuit for the switch machine. In other words, the energization of the reverse contactor R causes the motor of the switch machine to be 25 operated in a reverse direction by closing a circuit from the positive bus 12, through wires 28, 38 and 39, front contact 37 of reverse contactor R, field winding F, back contact 40 of normal contactor N, wire 41, armature A, wire 42, to the negative bus 14. This circuit causes the reverse 30 operation of the switch machine, but during this operation the switch machine cannot be stopped in mid stroke upon the detector track section becoming occupied by opening the pick-up circuit for the reverse contactor R at open front contact 34, as the current flow in the holding winding 10 is sufficient to hold contact 37 in a picked up or energized position.

35 As soon as the switch machine SM has unlocked the track switch TS, the movable contacts 4 and 5 are operated to intermediate or mid stroke positions in which the contacts 3-5 are made. Thus, during such mid stroke conditions, if the contact 6 is returned to a normal position 40 as a result of the return of lever SML to a normal position, the reverse contactor R will be deenergized closing back contact 37 and the normal contactor N will be energized, closing its front contact 40, thereby reversing the operation of 45 the switch machines. This assumes of course that the detector track section is not occupied, and that the operation of the lever SML must be governed in accordance with the usual interlocking associated therewith, the usual approach locking, detector locking and the like, in accordance with the usual signalling practices.

50 However, assuming that the switch machine continues the reverse operation, at the end of the operating stroke after the track switch TS has assumed its reverse locked position, the contacts

4 and 5 are operated to their reverse extreme positions. The opening of contacts 2-4, opens the energizing circuits for both the pick-up and holding windings 8 and 10 thereby allowing the contactor R to be deenergized for closing back contact 37 deenergizing the motor armature A and field winding F; while the continued closure of contacts 3-5 maintains the system in a condition permitting the normal operation of the track switch.

55 It is believed that the opposite operation will be readily understood by analogy to the operation already described, as such operation is merely the converse of that already described.

60 Whenever the detector track section associated with the track switch TS is occupied, the track relay T is deenergized thereby preventing the initiation of a new operation. For example, assuming the track switch to be in a normal position and the track relay T to be deenergized when the operator moves the control lever SML to a reverse position, the control relay responds as usual by operating the polar contact 6 to a right hand position, thereby closing the holding circuit for the reverse contactor R but the usual circuit for the pick-up winding 8 is opened at open front contact 34, which prevents the response of the reverse contactor R. It is to be noted, however, that a circuit is completed from the positive bus 12 through wires 28 and 29, polar contact 6 of relay CR in a right hand position, wire 30, point detector contacts 2-4, wire 31, holding winding 9 of normal contactor N, wire 44, to the negative bus 14. 100 As this circuit includes three windings in series, the resistance of the circuit is sufficiently high to limit the current flow in the pick-up winding 8 of the reverse contactor R to a value below that which will cause the actuation of contact 37 to an 105 energized position. Also, as the current flows differentially in the windings 7 and 9 of the normal contactor N, and as the current is of very low value, the contacts of this contactor likewise remain in retracted positions.

110 Thus, when the track relay T is deenergized and front contact 34 is open, the contactors N and R are energized only to a very low degree, which degree of energization is below that which is required to actuate their contacts to energized positions.

115 The normal and reverse contactors N and R preferably have associated therewith suitable magnetic blow-out means so that the arcs created at front contacts 37 and 40 will be readily extinguished. Also, these contactors preferably have associated therewith suitable overload protective means together with means for causing the interruption of either the normal or the reverse contactor pick-up and holding circuits upon the occurrence of such an overload so as to prevent the continual operation of the switch machine motor, but which means still permits the operator to govern the switch machine so as to return the track switch to its former position, all of 120 which has been more completely disclosed and described in the patent to Hoppe and Swanton, Pat. No. 1,877,876, dated September 20, 1932.

125 *Summary.*—Thus, a remote control circuit for switch machines has been disclosed in which the power is transmitted directly to the switch machines where it is applied locally to their operating circuits in accordance with remote manual control and in accordance with adequate detector locking means local thereto. The remote manual 130

control is effected over polarized circuits governed by manually operable levers and repeated by two position polar relays; while the detector locking is accomplished by the use of marginal type contactors or relays for governing the operating circuits of the respective switch machines, which contactors are controlled by their respective polar relays and their respective detector track sections.

5 A system, thus organized in accordance with the present invention, provides reversibility of a track switch in mid-stroke, prevents initiation of the track switch during the occupied condition of the associated detector track section, and permits the completion of an operation already initiated upon the detector track section becoming occupied.

10 Having described a switch machine control system as one specific embodiment of the present invention, it is desired to be understood that this form is selected to facilitate in the disclosure of the invention rather than to limit the number of forms which it may assume; and, it is to be further understood that various modifications, adaptations and alterations may be applied to the 15 specific form shown to meet the requirements of practice, without in any manner departing from the spirit or scope of the present invention except as limited by the appended claims.

What I claim is:—

30 1. In combination; a railroad track switch; a detector track section associated with said track switch; a switch machine having a motor for operating said track switch; normal and reverse contactors each having a pick-up winding and a holding winding said contactors respectively governing the normal and reverse operation of said motor; and means manually operable for energizing said holding winding of either said normal contactor or said reverse contactor independently of the condition of the pick-up windings, and for effectively energizing said pick-up winding of either said normal contactor or said reverse contactor only when said detector track section is unoccupied.

45 2. In a control system for railroad track switches, a switch machine for operating a track switch, point detector contacts having normal reverse and mid stroke positions, normal and reverse contactors each having pick-up and holding windings and each being actuated only when both of its windings are energized, a detector track section having a track relay associated with said track switch, a control relay having a polar contact operable to opposite extreme positions, means for manually governing said control relay, an energizing circuit for the holding winding of said normal contactor closed when said polar contact is in a position out of correspondence with said point detector contacts namely in reverse or mid stroke positions, an energizing circuit for the pick-up winding of said normal contactor closed only if said track relay is energized and when said polar contact is in a position out of correspondence with said point detector contacts namely in reverse and mid stroke positions, an energizing circuit for the holding winding of said reverse contactor closed when said polar contact is in a position out of correspondence with said point detector contacts namely in normal or mid stroke positions, an energizing circuit for the pick-up winding of said reverse contactor closed only if said track relay is energized when said polar contact is in a position out of correspondence with said point detector contacts namely in normal and

mid stroke positions, normal and reverse operating circuits for said switch machine governed respectively by said normal and reverse contactors.

5 3. In a traffic controlling system for railroads, a track switch, a switch machine for operating said track switch and having an operating circuit, a marginal contactor for governing said operating circuit said contactor having pick-up and holding windings both of which must be energized to actuate said contactor but the holding winding of which need only be energized to maintain said contactor actuated, a track relay associated with said track switch for indicating train presence, means for closing an energizing circuit for said pick-up winding only when said track relay indicates the absence of trains, and means for closing an energizing circuit for said holding winding independently of said track relay, whereby said marginal contactor is effectively actuated only when both of its windings are energized, and whereby said marginal contactor is maintained actuated if only its holding winding is energized.

10 4. In a traffic controlling system for railroads, a track switch, a switch machine for operating said track switch and having operating circuits, a marginal contactor for governing said operating circuits, said contactor having pick-up and holding windings both of which must be energized in order to actuate said contactor, a track relay associated with said track switch for indicating train presence adjacent said track switch, means for closing an energizing circuit for said pick-up winding only when said track relay indicates the absence of all trains and dependent upon the operated condition of said switch machine, and means for closing an energizing circuit for said holding winding independently of said track relay but dependent upon the operated condition of said switch machine, whereby said contactor is actuated only if both of said windings are effectively energized.

15 5. In combination; a track switch; a switch machine; point detector contacts jointly operated by said track switch and said switch machine; a detector track section; a manually controlled relay; normal and reverse operating circuits for said switch machine; normal and reverse contactors for closing said normal and reverse operating circuits respectively, said contactors being actuated to picked up positions only with a relatively high flux density but capable of being maintained picked up with a relatively low flux density; pick-up circuit means controlled by said manually controlled relay for selectively setting up said high flux density in said normal and reverse contactors dependent upon said point detector contacts and the unoccupied condition of said detector track section; and holding circuit means for maintaining the actuated normal or reverse contactor picked up by providing a flux density of said low value independently of the occupied condition of said detector track section until said switch machine completes its stroke as indicated by said point detector contacts; whereby an operation of said switch machine can be initiated only when said detector track section is unoccupied but which can be completed irrespective of such occupied condition and irrespective of the time required for such completion of the operation.

20 6. In combination, a distant track switch, a track relay for manifesting the presence of a train near said track switch, a switch machine for operating said track switch, a control relay for con-

- trolling said switch machine and having a pick-up circuit and a holding circuit, and a free and non-lockable lever for closing said pick-up circuit for said control relay only when said track relay is energized and for closing said holding circuit of said control relay irrespective of the conditions of said control relay or said track relay, whereby operation of said switch machine may be initiated only when said track relay is energized but such operation may be discontinued at any time. 80
- 10 7. In combination, a distant track switch, a track relay for manifesting the presence of a train near said track switch, a switch machine for operating said track switch, a control relay for controlling said switch machine and having a pick-up circuit and a holding circuit, a free and non-lockable lever for closing said pick-up circuit for said control relay only when said track relay is energized and for closing said holding circuit of said control relay irrespective of the conditions of said control relay or said track relay, whereby operation of said switch machine may be initiated only when said track relay is energized but such operation may be discontinued at any time, and 85
- 15 20 25 means for dropping said relay when said switch machine has completed its stroke. 90
8. In combination, a track switch, a switch machine for operating said track switch, a double winding relay for when energized applying current to said switch machine, said windings being constructed to cause said relay to assume its attracted position when said windings are energized in multiple and to cause it to remain in its attracted condition if said relay has been picked up and said windings are energized in series but to prevent said relay picking up when said windings are energized in series, means for applying current to said windings, and means for preventing the application of current to said windings in multiple when there is a train approaching said track switch. 95
9. In combination, a track switch, a switch machine for operating said track switch, two double winding relays either of which when energized applying current to said switch machine, said windings being so organized that when current is applied at one point the windings of one of said relays will be connected directly in multiple and the windings of said other relay will be shunted and when current is applied to another point the windings of said other relay are connected directly in multiple and the windings of said one relay are shunted, and means for preventing the windings of either of said relays to be connected directly in multiple when there is a train approaching said track switch. 100
